UNITED STATES PATENT OFFICE.

WILLIAM F. HALLEY, OF QUINN, SOUTH DAKOTA.

TRACE-CARRIER.

1,168,197.

Specification of Letters Patent. Patented Jan. 11, 1916.

Application filed June 30, 1915. Serial No. 37,332.

To all whom it may concern:

Be it known that I, WILLIAM F. HALLEY, a citizen of the United States, residing at Quinn, in the county of Pennington and State of South Dakota, have invented certain new and useful Improvements in Trace-Carriers, of which the following is a specification.

The present invention relates to a new and improved trace carrier that may be employed in any desired position on the harness, the purpose thereof being to receive the cockeye at the end of the traces and support the latter when they are in an inoperative position; and the principal and most important object of my invention is to provide a device of this character which includes a means for facilitating the attachment of the device at any suitable position on the harness, means to yieldably retain the cockeyes in place and means to facilitate the attachment and the removal of the respective cockeyes.

Another object of this invention is to provide a device of the above nature which includes a retaining member which coacts with a pair of retaining studs, so as to prevent the accidental removal or displacement of the cockeyes, and a spring for yieldingly supporting said retaining member and to facilitate its quick and easy operation.

A further object of this invention resides in the provision of a retaining member as above set forth which is so arranged as to completely protect the adjacent spring, so as to eliminate entrance of moisture and consequently greatly increase the longevity thereof.

A still further object of my invention is to provide a device of the type in question which consists of but a few simple parts and which, it is believed, may be manufactured at a comparatively low cost.

Various other objects and advantages will become apparent during the continuance of the following description.

The above and other objects which will become apparent are accomplished by such means as are shown in their preferred form in the accompanying drawings, described in the following specification and then more specifically pointed out in the appended claims.

In the accompanying drawings wherein like characters designate like parts throughout the several views; Figure 1 is a plan

view of my invention showing the retaining cover in an operative position. Fig. 2 is a transverse sectional view taken on line 2—2 of Fig. 1. Figure 3 is a plan view of my invention showing the retaining member in an inoperative position. Fig. 4 is a transverse sectional view taken on line 4—4 of Fig. 3, and illustrating a cockeye in place in connection with one of the retaining 65 studs.

In the drawings the numeral 10 designates the body portion or base plate of my improved device which, as is shown, is formed substantially disk shaped. The base plate 70 10 carries an upstanding core 11 which is open at its lower end, and which carries a plate 12 at its upper end, the purpose of this core being presently set forth. The base plate 10 also carries a pair of oppositely 75 arranged segmental side portions 13 which in turn are provided with inwardly projecting cover members 14. Upon reference to Fig. 3 it will be noted that the inner edges of the cover member 14 are spaced 80 some distance apart. However I have provided means for completing the cover of the device which will be presently described. The said base plate 10 is further provided with a pair of upstanding retaining studs 85 15 which are arranged in alinement with the core 11 and spaced from the respective terminals of the side portions 13. The studs 15 serve to receive the cockeyes which are carried on the respective trace members as 90 clearly illustrated in Fig. 4. An improved retaining plate 16 is now provided which carries a depending pin 17, the latter projecting downwardly through the plate 12 95 into the core 11 and carrying a removable fastening member 18. For the purpose of retaining the plate 16 in engagement with the respective top portions 14 and the upper ends of the studs 15, a coil spring 19 is arranged in the core 11 between the plate 12 100 and the member 18. When the retaining plate 16 is in its normal operative position the same lies snugly on the upper ends of the studs 15 while its upper face assumes a position which is flush with the upper face 105 of the cover portions 14. However as the plate 16 projects slightly beyond the outer edge of the cover portions 14 and is slightly longer than the diameter of the base plate 10, the same may be elevated to a certain 110 extent and moved a half-turn to assume the position shown in Fig. 3 and thus allow ac-

cess to the retaining studs 15. When the plate 16 is in this latter position, the cock-eye such as shown at 20 may be easily and quickly arranged in position over either of the studs 15. The fact that the plate 16 projects slightly beyond the outer edges of the cover portion 14, greatly facilitates its manipulation by reason of the fact that the operator may grip the same conveniently.

10 The base plate 10 also carries means for facilitating its attachment to certain portions of the harness. This means consists of a strand of heavy wire which is arranged about the perimetral edge of the said plate 15 and bent to form a plurality of strap engaging portions 21.

While I am not limited to any certain form of means for securing the strand of wire 22 in place, it is pointed out the same 20 may be soldered thereto and that this form has proven very efficient in practical operation.

As pointed out above the plate 16 is so arranged as to completely protect the coil spring 19 and to prevent the entrance of extraneous matter which would undoubtedly tend to cause the rapid deterioration thereof. Thus by this simple and compact structure the longevity of the spring is materially increased and therefore it is believed that the same forms a very important feature of the present invention. It will also be noted that the core 11 is open at its lower end in order to permit easy operation of the fastening member 18 and the correct placing of the coil spring 19 and therefore providing for the quick assembling of the several parts.

From the foregoing it is believed that the 40 advantages and novel features of my invention will be readily understood and therefore further detailed description is deemed unnecessary.

In reducing my invention to practice I 45 find that the form referred to herein as the most practical and preferred embodiment is the most efficient, but realizing that certain conditions will necessarily vary in concurrence with the adoption of my device, I desire to emphasize the fact that various 50 minor changes in the details of construction and in the proportion of parts may be re-

sorted to when required without sacrificing any of the advantages of my invention as defined in the appended claims.

Having thus fully described my invention, what I claim as new and desire to secure by Letters Patent is:

1. In a trace carrying device, a base plate having a plurality of strap engaging portions, an upstanding core carried by said base plate, said core being open at its lower end and closed at its upper end through the medium of a plate, a pair of segmental side portions carried by said base plate, cover portions carried by said side portions, a pair of retaining studs fixed to said base plate and arranged in alinement with said core, a retaining plate, a pin depending from said retaining plate and extending within said core, a fastening member carried on said pin within said core, and a coil spring interposed between said second mentioned plate and said fastening member, as and for the purpose set forth and described.

2. In a trace carrying device, a base plate having a plurality of strap engaging portions, an upstanding core formed on said base plate, the lower end of said core being open, a plate carried at the upper end of said core, a pair of retaining studs fixed to said base plate and alined with said core, a pair of segmental side portions carried by said base plate, cover portions carried by said side portions, a retaining plate of greater length than the diameter of said base plate, said retaining plate normally resting on the upper ends of said studs, the upper face of said retaining plate being flush with the upper face of said cover portions, a pin depending from said retaining plate and projecting into said core, a member fixed on said pin and arranged within said core, and a coil spring arranged about said pin and interposed between said second mentioned plate and said member, as and for the purpose set forth and described.

In testimony whereof I affix my signature in presence of two witnesses.

WILLIAM F. HALLEY.
